UNITED STATES PATENT OFFICE

2,074,276

APPARATUS FOR ARC WELDING

Raoul Jean Schmerber, Brussels, Belgium, assignor to La Soudure Electrique Autogène Société Anonyme, Brussels, Belgium

Application February 28, 1935, Serial No. 8,774
In France March 5, 1934

1 Claim. (Cl. 219—8)

In previous patent application No. 677,721 filed the 26th of June 1933, (now Patent No. 1,997,238) there is described a method of feeding an arc welding circuit with alternating current consisting in applying across the electrode and the object to be welded at each alternation a difference of potential the open circuit curve of which exhibits at the beginning of the alternation only and during a small fraction of the total duration 5 of the alternation a peak which corresponds to the voltage which is necessary and sufficient for striking the arc and subsequently during nearly the whole of the remainder of the alternation a substantially horizontal stretch which corresponds to the voltage which is necessary and sufficient for maintaining the arc.

This method has been carried out, when feeding from a three-phase source, by employing two transformers, one of which is termed the principal or main transformer and is capable of developing on open circuit in its secondary a difference of potential merely sufficient to maintain the arc which is assumed to have been struck. The other, which is termed the auxiliary transformer, has its primary fed by the phase which is 120 electrical degrees in advance relatively to the phase which supplies the primary of the principal transformer and is capable of developing on open circuit in its secondary, a peak 10 of voltage which is sufficient to strike the arc. In the said previous patent application, there is described an apparatus of this type in which the secondaries of the two transformers are connected in parallel.

35 The present invention has for object an apparatus which has a more effective action than the apparatus described in the said previous patent application.

To this end, according to the invention, one or 40 more generators or transformers capable of developing on open circuit a difference of potential sufficient for maintaining an arc after having been struck is or are connected in series with one or more generators or transformers capable 45 of developing on open circuit a peak of voltage which is sufficient for striking the arc. This connection in series is effected in such a manner that the generated electromotive forces are added together with the supplementary condition that 50 these electromotive forces are out of phase so that the peak voltage which serves to strike the arc occurs at the beginning of the alternation of the voltage for maintaining the arc.

In the case where the apparatus comprises 55 two transformers, the primaries of which are

connected as aforesaid, and the secondaries may supply the differences of tension also as aforesaid, the secondary of the auxiliary transformer, according to the invention, is connected in series with the secondary of the principal transformer in such a manner that the electromotive forces generated in the two windings are added together.

By this arrangement, not only is the action of the auxiliary transformer more effective, as it 10 has been proved by experience, but the circulating currents between the secondaries are automatically suppressed.

It suffices that the two transformers have drops of tension compatible with a stable operation of the arc, or in other words, that the difference of potential at the terminals of the latter drops to about 25 volts on closed circuit, which can be easily carried out by any competent welder.

An apparatus according to the invention may be provided by employing for the principal transformer and for the auxiliary transformer two single-phase transformers, the primaries of which are in V-connection to the terminal of 25 the supply network which is assumed to be a three-phase network.

But it is preferred to use as the main transformer a three-phase-single-phase transformer the primary of which is in V-connection with the 30 network and as auxiliary transformer a single-phase transformer, of which the primary is connected to the terminals at the extremities of the V.

This latter form of connection has the advantage that the phases of the supply network are 35 better balanced. In effect, the primary of the auxiliary transformer forms the third phase which exists only virtually in the ordinary form of V-connection. The three line currents can 40 thus be in the ratio 0.8—1—0.8, whereas with ordinary three-phase-single-phase transformers the ratio is 0.5—1—0.5.

The invention will now be described with the aid of the accompanying drawing, which shows 45 diagrammatically and by way of example two embodiments of an apparatus according to the invention.

In the drawing:—

Figure 1 shows diagrammatically one form 50 of apparatus according to the invention comprising two single-phase transformers the primaries of which are in V-connection with the terminals of a three-phase supply network.

Figures 2, 3 and 4 are curves showing re- 55

spectively the open circuit voltage during one alternation of the supply source at the terminals of the secondary of the main transformer, at the terminals of the secondary of the auxiliary transformer and across the electrode and the object to be welded.

Figure 5 illustrates diagrammatically another form of apparatus in accordance with the invention which comprises a three-phase single-phase main transformer, of which the primary is in V-connection with the terminals of a three-phase supply network, and an auxiliary single-phase transformer of which the primary is connected to the ends of the V.

Figure 6 represents the curves of the tension on closed circuit and of the welding current of an apparatus according to the invention, the curves having been registered by an oscillograph.

In the various figures like numerals represent like parts.

Referring to Figure 1, 1, 2 and 3 represent the three supply lines of a three-phase network of which the sequence of the phases is 1-2, 2-3, 3-1. The primary 4a of a single-phase transformer 4, hereinafter termed the auxiliary transformer, is connected to the phase 1-2 which is electrically 120° in advance of the phase 2-3. The power of this auxiliary transformer is relatively small and is, for example, of the order of 30-40% of the power of the main transformer which is to be used with it. These figures, however, are given by way of example.

The primary 5a of a single-phase transformer 5, hereinafter termed the main transformer, is connected to the phase 2-3 which is electrically 120° behind the phase 1-2. The primaries of the two transformers are in V-connection. The main transformer 5 is an ordinary arc welding transformer but is constructed in such a way that it develops an open circuit voltage which is necessary and sufficient to maintain the arc. On open circuit the voltage from the two transformers is for example 45 to 55 volts. The voltage striking the arc may be, for example, 2 to 2.5 times the voltage read on the voltmeter.

The transformer 5, like all ordinary welding transformers, is a transformer having a drooping load characteristic. The difference of potential which is maintained on load by the two transformers at the terminals of the arc is about 25 volts.

The curve which represents the open circuit voltage of the secondary is for example of the kind represented by the curve 10 in Figure 2. This curve should be as nearly as possible sinusoidal.

The auxiliary transformer 4 is an ordinary transformer having two cores and two yokes of which the core of the secondary is constructed in such a way that it is rapidly saturated by the flux produced by the current in the primary. For this purpose the core is made for example of a metal having a high magnetic permeability such as permalloy. In this way the primary sinusoidal wave is transformed into a secondary wave of peaked form.

The auxiliary transformer can also be constructed by providing a recess in the magnetic circuit which can then be constructed with ordinary metallic sheets. A third core which serves as a magnetic shunt may be provided in this case in order to permit the leakage flux to be adjusted by the variation of the size of an air-gap, provided in the core.

The curve which represents the open circuit voltage in the secondary of the auxiliary trans-

former is for example similar to the curve 22 illustrated in Figure 3.

The secondary winding 5b of the main transformer is connected in series with a secondary winding 4b of the auxiliary transformer in the welding circuit which comprises the electrode 3 and the object 9 to be welded (see Figure 1). This connection is made in such a way that the voltages generated are added together. The secondary winding 4b must obviously be able to take the welding current. The welding current can be regulated by any suitable regulating means, for example by a self-induction coil 23 provided with contacts 24 over which an arm 25 can be moved.

Owing to the fact that the auxiliary transformer is supplied by the phase which is electrically 120° in advance of the phase which supplies the principal transformer, there is obtained an open circuit voltage curve of the type represented by the curve 14 in Figure 4, which shows that the peak voltage is produced at the beginning of the alternation. This curve is an enlargement of an oscillograph record. It must be mentioned that, owing to the two curves of Figures 2 and 3 being out of phase and having different form factors, the secondary voltages of the two transformers are not added arithmetically, and that these voltages should be in such a ratio that the resultant wave can be represented by the curve indicated at 14 in Figure 4.

Experience has proved that the passages by zero of the voltage curve on closed circuit are more quick when the secondaries of the two transformers are connected in series than when they are connected in parallel at the terminals of the arc and that on the other hand the stability during welding is increased.

In practice, it is advantageous to employ, as the main transformer, a three-phase-single-phase transformer of which the primary winding is in V-connection with the terminals of the supply and, as the auxiliary transformer, a single-phase transformer of which the primary is connected to the extremities of the V.

An apparatus of this type is illustrated diagrammatically in Figure 5. The phases 1-2 and 2-3 supply the primary 5'a of the principal transformer 5' which is in V-connection. The phase 3-1 supplies the primary 4a of the auxiliary transformer 4. The two primaries are thus connected in Δ -connection to the supply network. The secondaries 5'b and 4b remain connected in series in the welding circuit and in such a way that their voltages are added together. In this way a better balance of the load on the three phases of the supply network is obtained than with ordinary three-phase-single-phase transformers with which the currents in the three phases are in the ratio 0.5-1-0.5.

In Figure 6, there is represented an oscillograph record of the tension on load at the terminals of the arc and of the welding current.

It will be noted at the point 17a of the curve 17 which represents the tension on load a drop of tension produced by the passage of a drop of metal from the electrode to the object to be welded, this drop of metal having produced a partial short-circuit. It will also be noted at the point 26a of the curve 26 which represents the welding current the increase of current which has been produced by this partial short-circuit. It can also be noted the action of the auxiliary transformer at this moment, which almost instantaneously has brought back the arc voltage to its normal value.

In addition to the case of striking the arc and keeping it stable in spite of the low voltage, the apparatus in accordance with the invention effects great economy in power as compared with ordinary welding transformers and the power factor of the installation is considerably improved.

What I claim is:

An apparatus for feeding an arc welding circuit from a three-phase source of alternating current, comprising a three-phase single phase principal transformer capable of developing on open circuit in its secondary, for each alternation of the source of current, a difference of potential sufficient for maintaining an arc after having been struck, a single-phase auxiliary transformer capable of de-

veloping on open circuit in its secondary, for each alternation of the source of current, a difference of potential represented by a curve with one sharp peak whose apex corresponds to a difference of potential sufficient to strike the arc, a connection for branching the primary of the principal transformer in V-connection with the three-phase source of current, a connection for branching the primary of the auxiliary transformer to the terminals at the extremities of the V, and connections for connecting in series the secondaries of the two transformers in such a manner that the generated electromotive forces are added together.
